CLAIM

The ornamental design for a pivot hinge as shown and described.

DESCRIPTION

FIG. 1 is a front-top-left perspective view of a pivot hinge showing my new design;

FIG. 2 is a back-bottom-right perspective view thereof;

FIG. 3 is a left side view thereof;

FIG. 4 is a right side view thereof;

FIG. 5 is a back view thereof;

FIG. 6 is a front view thereof;

FIG. 7 is a top view thereof;

FIG. 8 is a bottom view thereof;

FIG. 9 is a front-top-left exploded perspective view thereof;

FIG. 10 is a front-top-right exploded perspective view thereof;

FIG. 11 is back-top-left a perspective view of the pivot hinge and the pivot hinge in its environment of use;

FIG. 12 is a front-bottom-right perspective view of the pivot hinge and the pivot hinge in its environment of use;

FIG. 13 is a front-top-left perspective view of a first part of the pivot hinge;

FIG. 14 is a back-left perspective view thereof;

FIG. 15 is a left view thereof;

FIG. 16 is a right view thereof;

FIG. 17 is a back view thereof;

FIG. 18 is a front view thereof;

FIG. 19 is a top view thereof;

FIG. 20 is a bottom view thereof;

FIG. 21 is a front-top-left perspective view of a second part of the pivot hinge;

FIG. 22 is a back-left perspective view thereof;

FIG. 23 is a left view thereof;

FIG. 24 is a right view thereof;

FIG. 25 is a back view thereof;

FIG. 26 is a front view thereof;

FIG. 27 is a top view thereof;

FIG. 28 is a bottom view thereof; and,

FIG. 29 is a perspective view of the pivot hinge incorporated into a frame.

(Continued)

The broken lines depict environmental subject matter that forms no part of the claimed design.
